UNITED STATES PATENT OFFICE

168,709

PORTABLE TYPEWRITER CASE OR
SIMILAR ARTICLEJean O. Reinecke and Jon W. Hauser, Oak Park,
Ill., assignor to Hawley Products Company, St.
Charles, Ill., a corporation of Delaware

Application July 7, 1950, Serial No. 10,994

Term of patent 14 years

(Cl. D87—6)

To all whom it may concern:

Be it known that we, Jean O. Reinecke and Jon W. Hauser, citizens of the United States, residing at Oak Park, in the county of Cook and State of Illinois, have invented a new, original, and ornamental Design for a Portable Typewriter Case or Similar Article, of which the following is a specification, reference being had to the accompanying drawing, forming part thereof in which:

Fig. 1 is a top view of the portable typewriter case or similar article embodying my new design;

Fig. 2 is a side view of the portable typewriter case or similar article; and

Fig. 3 is an end view thereof.

We claim:

The ornamental design for a portable typewriter case or similar article, substantially as shown.

JEAN O. REINECKE.
JON W. HAUSER.
